UNITED STATES PATENT OFFICE.

WILLIAM H. DONLEY, OF SPRINGFIELD, MASSACHUSETTS.

MOUTHPIECE FOR BOILER-FURNACES.

SPECIFICATION forming part of Letters Patent No. 699,500, dated May 6, 1902.

Application filed January 14, 1902. Serial No. 89,670. (No model.)

To all whom it may concern:

Be it known that I, WILLIAM H. DONLEY, a citizen of the United States, residing at Springfield, in the county of Hampden and State of Massachusetts, have invented certain new and useful Improvements in Mouthpieces for Boiler-Furnaces, of which the following is a specification.

My invention relates to improvements in mouthpieces for boiler-furnaces; and the object of my invention is the provision of a mouthpiece constructed to be placed in the fore part or front of a furnace and which can be produced at a comparatively low price and which mouthpiece will prevent the usual waste of heat, thus proving a great saving in fuel; which will prevent the destruction of the lining of the door; which will save much repair to the furnace, and which will generally prove efficient and practical.

To attain the desired objects, the invention consists of a hollow braced mouthpiece fitting in the furnace and serving to sustain the walls of the furnace and having means to allow a passage of water to insure the proper temperature of the mouthpiece and to prevent destruction of the same by excessive heat.

The invention further consists of a hollow water-lined mouthpiece adapted to be placed in the fore part of the furnace adjacent to the door and embodying novel features of construction and combination of parts, substantially as disclosed herein.

In order that the details of construction and the application of my mouthpiece may be thoroughly understood, as well as its many advantages be fully appreciated, I invite attention to the accompanying drawings.

Figure 1 represents a front view of a portion of a boiler and furnace with my novel mouthpiece applied, showing the manner of connection and the relations of parts when in operative position. Fig. 2 represents a perspective view of the mouthpiece detached. Fig. 3 represents a vertical transverse sectional view of the mouthpiece. Fig. 4 represents a vertical longitudinal sectional view thereof, and Fig. 5 represents a detail view showing the construction of the braces and partitions with the water-passages of the mouthpiece.

Referring by numerals to the drawings, in which similar numerals of reference denote corresponding parts in the several views, the 55 numeral 1 designates the boiler, and 2 designates the mouthpiece, which is placed in the front of the furnace 3, adjacent to the door, and leading from the boiler are the pipes 4, which enter the hollow mouthpiece and supply the water for circulation through the said mouthpiece, and leading from the mouthpiece is the discharge-pipe 5, the purpose of which is to draw off sediment or foreign matter from the mouthpiece when found necessary, and 65 each of the pipes is provided with a suitable cock or faucet 6 for opening and closing the said pipes. From this construction it is evident that my mouthpiece is placed in the front of the furnace, and being made of heavy 70 material—such as cast-iron, sheet-iron, or cast-steel—will serve to brace and strengthen the furnace, and the circulation of water through the mouthpiece will keep the same in a cool condition, this preventing excessive 75 heat from contact with the lining of the door, also that it will drive the heat in or retain it in the furnace, and thus save much fuel and also save considerable in repair to the furnace.

My mouthpiece is of peculiar construction and is composed of the front section 7, having the inner wall 8, which is connected with the outer wall 9 by means of the braces 10, which also form a series of water chambers 85 or jackets 11, the said braces or division-walls being each provided with an outlet or opening 10', the purpose of which is to establish communication between the jackets or chambers and permit a free circulation of water 90 to all the jackets, and the rear section is composed of a vertical wall 12, having an inner wall 13, which is similar to the inner wall of the other section, and this section is provided with similar braces or division-walls 14, which 95 are also provided with an outlet or opening 14', the purpose of which is to permit free passage of water to all the jackets or chambers 15, provided in said section. From this construction it will be seen that the mouthpiece is hollow and strongly braced by the horizontal and vertical division-walls and that a series of chambers or jackets are provided which permit the free circulation of

water through the entire mouthpiece. It will also be seen that the flow of water and the cleaning or removing of sediment from the mouthpiece is under perfect control.

5 My novel mouthpiece can be applied to the well-known and common construction of furnaces in general use at a low price and will add greatly to the efficiency of the furnace and to the life and usefulness thereof, and 10 its many advantages will commend it as a much-needed and practical improvement.

I claim—

1. The combination with a boiler-furnace, a hollow metal mouthpiece fitting therein, and 15 extending around the entire mouth of the furnace, a series of braces or division-walls in the mouthpiece having openings, and forming water jackets or chambers, and water-supply means, and the draw-off pipe for sediment or foreign matter.

2. The combination with a boiler-furnace, the mouthpiece having a hollow compartment

extending around its entire construction, a series of perpendicular walls in the horizontal portion of the mouthpiece and a series of 25 horizontal walls in the vertical portions, said walls having openings and forming a series of communicating jackets or chambers, and water-supply means.

3. A mouthpiece for boiler-furnaces, consisting of a hollow casting adapted to fit the mouth of the furnace, division-walls in the casting connecting the walls of the mouthpiece and forming a series of water-jackets, 30 said division-walls each having an opening forming communication throughout the entire mouthpiece and also bracing the walls thereof.

In testimony whereof I affix my signature in presence of two witnesses.

WILLIAM H. DONLEY.
